UNITED STATES PATENT OFFICE.

SIDNEY BLENKHORN, OF CANNING, NOVA SCOTIA, CANADA.

OVERSHOE-LIFT.

SPECIFICATION forming part of Letters Patent No. 339,258, dated April 6, 1886.

Application filed September 7, 1885. Serial No. 176,334. (No model.)

To all whom it may concern:

Be it known that I, SIDNEY BLENKHORN, of Canning, in the Province of Nova Scotia, in the Dominion of Canada, have invented certain new and useful Improvements in Overshoe-Lifts; and I do hereby declare that the following is a full, clear, and exact description of the same.

The object of my invention is to readily pull on a rubber overshoe without touching it with the hand.

My invention consists of an implement consisting of two plates together forming a handle, having coinciding curved jaws to grip the edge of the shoe at the heel and spring apart, a catch to hold the jaws closed, and a roller which acts as a fulcrum when the lift is being used as a lever to elongate the overshoe at the heel, to run up the back of the boot while the overshoe is being put on by pulling the handle.

Figure 1 is a perspective view of my improved lift. Fig. 2 is a sectional elevation of the same as when in practical use.

A A' are two concaved strips, which combinedly make a straight handle, to be grasped by the operator in using the implement. The strips are joined together at one end, so as to

spring apart at the opposite ends, which are formed with jaws B B', coincidally curved to receive intermediately the upper edge of the back of the overshoe, and by closing the two parts of the handle, by squeezing them together, cause the jaws to grip the overshoe and be held by a spring-catch, C. The inner jaw, B, is provided with cheeks D, in which is journaled a roller, E, to run up the back of the boot when the overshoe is being slipped on. The roller forms a fulcrum by which the overshoe is elongated by inward pressure of the handle to cause the overshoe to pass freely over the heel of the boot.

I claim as my invention—

An overshoe-lift consisting of the two-part handle A A', having a spring-connection at one end and coinciding curved jaws B B' at the opposite end, to grip the back of the overshoe, spring-catch C, to hold the jaws closed, and roller E, to travel up the back of the boot when the overshoe is being pulled on, as set forth.

SIDNEY BLENKHORN.
